UNITED STATES PATENT OFFICE

HERMANN EBERHARDT, OF BRESLAU, GERMANY

APPARATUS FOR SORTING GUTS

Application filed March 9, 1929, Serial No. 345,874, and in Germany March 16, 1928.

Sorting apparatus have become known in which, opposite a stationary wall serving as an abutment and guide face for the articles to be measured, several movable wall elements or the like are arranged, spaced at different distances from the stationary wall.

Contrary to these known devices the apparatus for sorting guts according to the invention is of simpler construction and much easier to manipulate as the movable wall elements are formed by the front ends of suitable levers normally perpendicular to the wall and mounted on a common axle parallel to the stationary wall, said levers are adapted to be depressed so that their ends move in a direction approximately parallel to the stationary wall. This form of construction presents the advantage that upon insertion of the gut into the apparatus, it is at the same time measured so that the work is carried out very rapidly.

An embodiment of the invention is illustrated by way of example in the accompanying drawing in which:

Fig. 1 is a longitudinal section through the apparatus on line 1—1 of Fig. 2, showing the elements in the position which they assume during the measuring.

Fig. 2 is a top plan view of Fig. 1.

Fig. 3 is a side elevation of Fig. 1.

Fig. 4 shows on larger scale a top plan view in the direction of the arrow line *a* in Fig. 1.

A base plate 1 has at one end a stationary wall 10 and further bearings 2 in which an axle 3 is journaled parallel to said stationary wall. On said axle, several two-armed levers are pivotally mounted which are normally perpendicular to the stationary wall 10. The arms 4', 5', 6' . . . 9' of these levers are consecutively of different length, the front arms 4'', 5'', 6'' . . . 9'' of said levers possessing, owing to their hollow prismatic shape, a light overweight so that they come to rest upon a support 1' on the base plate 1, as shown in Fig. 2.

All the levers, with the exception of the lever 4', 4'', are shown in the lowered position.

The distance between this stationary wall

10 and the corresponding end of the several arms 4', 5', 6' . . . 9' of the levers is different, i. e. the distance *s*₄ between this wall 10 and the arm 4' is shortest (Fig. 4) the arm 9' being farthest distant from said wall, the distance *s*₉ between the wall 10 and the end of the arm 9' being the greatest distance.

The different distances of the ends of the arms of the levers from the stationary wall 10 correspond to the different gauges.

The levers are marked on the upper surface with different signs in accordance with corresponding gauges.

The operation is as follows:

The workman is standing before the apparatus at the side designated in Fig. 1 by a cross and looks in the direction of the arrow line *b*. He grips the gut D to be measured which is inflated and lowers it along the stationary wall 10 until it bears against the base plate 1. The arms of the levers situated in the direction of movement of the gut are thereby depressed around the axle 3 in the direction of the arrow line *b*. When the diameter *d* of the gut D is smaller than the distance *s*₄ between the end of arm 4' and the wall 10, none of the levers are depressed. If however the gut diameter *d* is greater than the distance *s*₄ but smaller than the distance *s*₅ only the lever 4', 4'' is depressed. If the diameter of the gut is greater than the distance *s*₅ but smaller than *s*₆ the levers 4', 4'' and 5', 5'' are depressed and so forth.

In the example illustrated the diameter *d* is greater than the distance *s*₄ but smaller than the distance *s*₅ so that the gut depresses only the lever 4', 4'' from the position indicated in dash lines into the position shown in full lines.

As mentioned above the levers have signs marked on the upper surface, three groups of signs being used. The arm of each lever (except the arm 4') is marked with two figures *p*, *q*, (Fig. 4) of which the lower figure *p* indicates the measure of the distance of the preceding arm from the stationary wall and the figure *q* the measure of the distance of the arm in question from this stationary wall. The arm 5' is marked for instance

with numerals 27 and 29, meaning that the distance s_4 between the end of the preceding arm 4' and the stationary wall 10 is 27 mms. and that the distance s_5 between the arm 5' and the stationary wall 10 is 29 mms.

At the inserting of an inflated gut D into the apparatus a number of levers, according to the thickness of the gut are depressed and the result of the measuring has to be read on the first lever which has not been depressed.

If the inflated gut D has at the insertion the levers 4', 4'' and 5', 5'', the lever 6', 6'' indicates that the diameter d of the gut D is greater than or similar to 29 mms. and smaller than 31 mms. If the inserted

gut D depresses only the lever 4', 4'', as shown in the drawing, the diameter d of the gut is similar to or greater than 27 mms. but smaller than 29 mms. The third group of signs r consists of consecutive numerals

1, 2, 3 . . . 6 and they serve for sorting the guts into groups. A gut which depresses only the lever 4', 4'' belongs to the group 2 and a gut which depresses the levers 4', 4'', 5', 5'' and 6', 6'', belongs to group 4. If upon insertion of a gut D none of the levers are depressed, it belongs to the group 1.

The third group of signs consists of dots t of different colors. The dot t on arm 4' is for instance green, that on arm 5' yellow, that on arm 6' white and so on. These differently coloured dots indicate the different groups for sorting so that the workman can sort according to the color of the dot on the oscillated lever.

These signs are not obligatory and other signs than those described may be used.

I claim:

A sorting apparatus especially for guts, comprising in combination with the base plate having a vertical front wall, an axle parallel to said wall and fixed on said base plate, and a number of levers normally perpendicular to said wall and pivotally mounted on said axle so that their corresponding ends are standing at different distances from said vertical wall, said levers being adapted to be depressed to move approximately parallel to said stationary wall.

In testimony whereof I affix my signature.
HERMANN EBERHARDT.
